UNITED STATES PATENT OFFICE.

THOMAS BURDEN, OF WARRNAMBOOL, VICTORIA, AUSTRALIA.

CORRECTION OF TYPE IN PRINTERS' GALLEYS.

Application filed September 11, 1922. Serial No. 587,575.

To all whom it may concern:

Be it known that I, THOMAS BURDEN, a subject of the King of Great Britain and Ireland, and a resident of the city of Warrnambool, in the county of Villiers, State of Victoria, Commonwealth of Australia, have invented certain new and useful Improvements Relating to the Correction of Type in Printers' Galleries, of which the following is a specification.

In the correction of errors in type in printers' galley it is the practice, after the type has been set either by hand or machine, to take a pull or proof of the set up type, this proof sheet being then checked and corrected by the proof reader after which the type in the gallery is corrected by reference to the proof sheet.

Such method of correction is objectionable owing to the strain on the eyesight and the time and labor involved in locating the lines of type requiring correction in the galley.

The object of the present invention is to provide a simple and effective means for quickly locating for correction errors in the set up or composed type thereby to a great extent overcoming the aforesaid objections and facilitating the type correcting operation besides resulting in greater accuracy.

The invention involves means for printing upon the proof sheet, as it is pulled from the type, a vertical row or column of index marks or characters such, for instance, as numerals, which are arranged consecutively one above another alongside the column of printed matter on the proof; and a suitable type line locator adapted for placing alongside the column of type in the galley, this locator bearing a second column of index marks or characters corresponding in appearance and relative position with the index marks on the proof sheet. Thus by referring to the index characters on the corrected proof sheet and to the corresponding characters of the locator the lines of type requiring correction may be instantly located.

Various constructional forms of device may be employed in carrying out the invention and it will be readily understood that the invention is not limited to the particular forms hereinafter specifically described

but embraces other alternative devices for effecting equivalent results.

Referring to the drawings which form part of this specification:—

Figure 1 is a plan of a galley of type with one form of device in accordance with the invention applied thereto.

Figure 2 is a diagram of part of a proof sheet bearing printed index characters in accordance with the invention.

Figure 3 is a perspective view of portion of the device seen in Figure 1.

Figure 4 shows portion of an alternative form of device in accordance with the invention.

Figure 5 illustrates the use of the device seen in Figure 4.

Figure 6 shows a further modification of the invention removed from the galley, part of which is seen in the background.

Figure 7 shows the embodiment seen in Figure 6 applied to the galley.

Figures 8 and 9 illustrate a further modification of the invention.

The invention includes a first vertical row or column of index numerals, letters or other suitable characters A formed in raised type or otherwise of a reproductive nature whereby they may be inked and printed on the proof sheet simultaneously with the lines of type which are indicated at B in the galley C.

The index characters A may be formed on a bar or like member D of metal or other suitable material, or on a separate metal strip E suitably attached to said bar-like member, the arrangement being such that the reproductive characters A are disposed "type-high" or at the same level as the type characters of the type lines B.

The column of index characters A extends longitudinally of the gallery and at right angles to the lines of type and such characters may be disposed opposite each line of type or as shown they may be spaced apart at a distance equal to several lines of type thus permitting of fewer and larger characters being employed. Horizontal graduation marks F may also be formed on the face of the bar-like member D adjacent the characters A and the adjoining ends of the type lines B. Such graduation marks, which are not intended for reproduction, may be dis-

posed opposite each line of type or otherwise spaced as desired.

In combination with the foregoing I employ a type line locator bearing a second vertical row or column of index numerals, letters or characters G which correspond in appearance and position, relative to the type lines, with the reproductive characters A. It will be noted that the latter index characters are inverted relative to the second column of characters G. The characters A thus correspond with the usual inverted position of the types which are placed upside down in the galley, the lower end of which coincides with the head of the type column, so that the resultant printed matter will read from left to right.

The second column of index characters G is not intended for reproduction and may be printed or otherwise inscribed or marked on the bar-like member D or other appropriately placed surface or on a metal strip H secured to the bar-like member. Preferably the characters G are marked or inscribed on white enamel, bright metal or some other easily cleaned material which will show up the characters clearly. Graduation marks I corresponding with the graduations F of the first column of index characters may also be marked on the surface H adjacent the characters G.

It will be evident that the particular constructional form of device employed in accordance with the invention may vary considerably, for instance, as illustrated in Figures 1 and 3 the bar-like member D may be formed integral with or suitably fixed to the galley C so as to form a permanent part thereof. It thus constitutes one of the side walls of the galley, against which wall the ends of the type lines B are placed as shown.

Alternatively, as seen in Figures 6 and 7, the bar-like member D may be formed separately from and adapted to be placed against the side of an ordinary galley C. In this case the member D may have formed on or attached to one of its ends a foot J which extends at right angles to the member D and is adapted to be placed against the adjacent end of the galley as in Figure 7 so that the columns of index characters A and G are kept squarely in position relative to the galley and the lines of type.

In both the embodiments illustrated in Figures 1 and 2 and Figures 6 and 7 it will be seen that the second column of index characters G is disposed at a lower level than the "type-high" column A so that the lower column G of non-reproductive characters will not be touched by the inking roller when the column A and the type lines B are being inked to print the proof sheet.

In the alternative embodiments seen in Figures 4, 5, 8 and 9, the bar D forms an entirely independent movable integer of sub-

stantially rectangular form in cross section and having a height approximating the height of the type lines and a width or thickness which may be considerably less than its height as shown. As seen in Figures 4 and 5 70 the reproductive column of characters A may be carried on one longitudinal side or face of the bar D whilst the second or type locating column of characters G is carried on the opposite longitudinal face of the bar. 75 By this means it is merely necessary to reverse or invert the bar, after the proof sheet has been pulled from the type and the characters A, so that the characters G thus face upwardly when the set up type is being corrected from the proof sheet. 80

When the bar D seen in Figure 4 is used, the galley may be provided with a longitudinal divisional wall K forming an elongated pocket or compartment L to accommodate the bar between said divisional wall and the adjacent outer side wall of the galley as in Figure 5. The bar is thus maintained firmly in position for use.

In the further embodiment shown in Figures 8 and 9, the first or reproductive column of index characters A is carried on one of the longitudinal sides or faces of the bar D whilst the second column of characters G is placed on one of the side faces at right angles to the face carrying the column A. It is thus merely necessary after the proof has been taken, with the bar D in the position shown in Figure 8, to lay the bar on its side adjacent the set up type with the characters G upturned as in Figure 9 for locating the requisite type lines. This latter form of the invention is particularly adapted for use with an ordinary galley, as the bar D may be placed in the galley as in Figure 8 and laid on one side thereof as in Figure 9.

In using the invention, ink is applied to the set up type and the positioned column of reproductive characters A and a pull taken therefrom on the proof sheet M (Figure 2). The result is that a column of printed characters N is transferred to the proof sheet by the raised or reproductive characters A alongside the printed lines O taken from the type B. The proof sheet is now corrected by the proof reader in the usual manner and the corrected proof sheet is then placed beside the galley. By the operator noting the printed characters N opposite or nearly opposite any particular line on the proof sheet and then referring to the corresponding index character of the type locating column G, which is now disposed beside the type B, he may immediately locate the required type line which is to be corrected. The latter may then be altered or removed or an omitted line inserted in the usual manner. In this regard it will be understood that the operation of correcting the set up type must 130

be started from the bottom of the galley or the "head" of the type column so that, in the event of two or more additional lines of type being inserted, the alignment of the type relative to the index characters will be preserved. Thus by working upwardly from the bottom of the galley only the type which has already been corrected is displaced.

To additionally facilitate the location of the required type lines, certain of the characters G may be distinguished from others by coloring or like means; for instance, when numerals are employed the numeral 10 and multiples thereof may be marked in one color and the other characters in a different color or odd and even numbers can be distinguished in a similar manner.

Having now described my invention what I claim as new and desire to secure by Letters Patent is:—

1. A device for the purpose indicated comprising means for printing a vertical row or column of index characters on the proof sheet simultaneously with the printing of the transverse lines of reading matter thereon, and a type line locator having a second vertical row or column of index characters adapted for disposition beside the lines of set-up type, the characters of said second column occupying substantially the same position relative to the lines of type as said printed index characters occupy in relation to the printed lines of the proof sheet.

2. A device for the purpose indicated comprising a vertical row or column of reproductive index characters adapted to extend longitudinally of the type galley to print a corresponding column of characters on the proof sheet simultaneously with the printing of transverse lines of reading matter thereon, and a type line locator having a second vertical column of index characters adapted for disposition beside the lines of set-up type, the characters of said second column being inverted in relation to said reproductive characters and occupying substantially the same position relative to the lines of type as the printed index characters occupy in relation to the printed lines of the proof sheet.

3. A device for the purpose indicated comprising a column of reproductive index characters adapted to extend longitudinally of the type galley to print a corresponding column of characters on the proof sheet simultaneously with the printing of the transverse lines of reading matter thereon, and a type line locator having a second column of index characters adapted for disposition beside the lines of set-up type, the characters of said second column being inverted in relation to said reproductive characters and occupying substantially the same position relative to the transverse lines of

type as the printed index characters occupy in relation to the printed lines of the proof sheet.

4. A device for the purpose indicated consisting of a bar-like member adapted to extend longitudinally of the type galley at one side thereof and carrying two columns of index characters, the characters of one column being of a reproductive nature and adapted to print a corresponding column at one side of the printed lines of reading matter on the proof sheet simultaneously with the printing of such lines, the characters of the other column corresponding in relative position with and being the same as the characters of the first column but of a non-reproductive nature.

5. A device for the purpose indicated comprising a bar adapted to be placed longitudinally of the type galley at one side of the set-up type, said bar carrying on one side thereof a column of raised or reproductive index characters adapted to be printed on the proof sheet simultaneously with the printing of the transverse lines of type thereon, and a second column of index characters carried on another side of said bar, whereby either of said columns may be brought into position for use by turning the respective side of the bar upwardly, substantially as described.

6. A device for the purpose indicated comprising a bar adapted to be placed longitudinally of the type galley at one side of the set-up type, said bar carrying on one side thereof a column of raised or reproductive index characters adapted to be printed on the proof sheet simultaneously with the printing of the transverse lines of type thereon, and a second column of index characters carried on the opposite side of said bar, whereby either of said columns may be brought into position for use by inverting the bar, substantially as described.

7. A device for the purpose indicated comprising a bar adapted to be placed longitudinally of the type galley at one side of the set-up type, said bar carrying on side thereof a column of raised or reproductive index characters adapted to be printed on the proof sheet simultaneously with the printing of the lines of type thereon, and a second column of non-reproductive index characters carried on another side of said bar, the characters of said second column being disposed in the same relative positions as those of the first column but being inverted in relation thereto.

8. A device for the purpose indicated comprising a bar adapted to be placed longitudinally of the type galley at one side of the set-up type, said bar carrying on one side thereof a column of raised or reproductive index characters adapted for printing on the proof sheet simultaneously with the

printing of the lines of type thereon, and a second column of index characters carried on the opposite side of said bar, whereby either of said columns may be brought into position for use by inverting the bar; in combination with a galley having a longitudinal partition forming a compartment

for said bar at one side of the galley substantially as described.

In testimony whereof I affix my signature. 10
